UNITED STATES PATENT OFFICE.

SHUBAEL T. ARMSTRONG, OF SYCAMORE, ILLINOIS, ASSIGNOR OF ONE-TENTH
TO FRED A. COLE, OF PLYMOUTH, MICHIGAN.

SMOKE-CONSUMING FURNACE.

SPECIFICATION forming part of Letters Patent No. 517,824, dated March 27, 1894.

Application filed April 13, 1893. Serial No. 470,145. (No model.)

To all whom it may concern:

Be it known that I, SHUBAEL T. ARMSTRONG, a citizen of the United States, residing at Sycamore, in the county of De Kalb, State of Illinois, have invented certain new and useful Improvements in Smoke-Consuming Furnaces; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to smoke consuming fire pots, and consists in a certain construction and arrangement of parts as hereinafter fully set forth, the essential features of which being pointed out particularly in the claims.

20 The object of the invention is to produce a fire-pot in which the construction is such as to insure a more complete combustion, and the consumption of the carbon and gases liberated from the burning coal. This object 25 is attained by the device illustrated in the accompanying drawings, in which—

Figure 1 is an elevation of my improved fire-pot or furnace, the front wall being broken away to show the arrangement of parts. Fig. 30 2 is a transverse section through the fire-pot and dampers. Fig. 3 is a plan of the fire-pot and its reversible damper or cover. Fig. 4 is a vertical section on line 4—4 of Fig. 2.

Referring to the letters of reference, A and 35 B designate two independent divisions of the fire-pot, separated by the adjacent partitions b, d, which form a flue a between their opposed faces. Said divisions are each provided with a grate C, and below each grate is 40 an ash-pit D.

E designates a reversible damper, having a cylindrical head F, which is journaled in the frame, slightly above and between the divisions of the fire-pot, and extending from 45 said head, through the front wall, is a shaft f, having a square end for the application of a crank, with which to actuate said damper. The form and location of the damper E are such, that, by means of its reversible feature, 50 it may be made to alternately cover and close

the top of each of the divisions. Said damper being provided on each side with a right angle flange c, adapted to fit over the upper edges of said divisions of the fire-pot, and may be made to set in a groove, to more perfectly prevent the escape of gas when the damper is closed. The cylindrical head of the damper is hollowed out, on opposed sides, between the circular ends h thereof, as shown at o, leaving a solid central portion which extends the entire length of the fire-pot, and from which the body portion E of the damper proceeds, as clearly shown in Fig. 2. The partitions d and b do not extend to the top of the fire-pot, but terminate some distance below the top 65 thereof, at a point where their vertical line intercepts the circumference of the head F. By which arrangement, when the damper E is in the position shown in Figs. 1 and 2, the solid portion of said head closes the opening 70 into division B above the portion d, and communication is established between the division A and the central flue a through the concavity in one side of said head. It will also be understood in this connection, that, by reversing said damper to the top of division B, 75 as shown by dotted lines, communication will be established between division B, and the flue a through the concavity in the opposite side of said head, and the solid portion of the head will at the same time close the opening 80 into division A, above the partition b.

H designates a lever pivoted on the shaft I. The upper end of said lever extends into the path of the solid portion of the head F, 85 and the lower end thereof is bifurcated and sits astride of the upper edge of the lower damper J, which extends the length of the fire-pot and is pivotally mounted, so that it may be alternately swung against the lower 90 edge of the partitions d, b of the respective divisions of the fire-pot.

The operation of the device is as follows:— With the parts in the position shown in Fig. 1, the fire is started on the grate in division 95 B, the top of which being open affords direct communication with the stack (not shown). When the fire so started has burned to a glow or incandescent heat, a fire is started upon the grate in division A, the damper in 100

door K is opened, and that in door L nearly closed, by which means the carbon and gases generated by the initial burning of the fuel in division A of the pot, are conveyed 5 out through the opening in the damper head F, down through the dividing flue a, and upward through the glowing fire in division B, in the intense heat of which said smoke and 10 gases are consumed, the carbon and gases before passing through the fire, being mixed with the air which enters in sufficient quantity through the partially closed damper in door L, to insure combustion. When the fire in division A has burned to a red heat, fresh 15 fuel is added to the fire in division B, the damper in door L opened, and the one in door K nearly closed. The damper E is then reversed to the dotted position shown in Fig. 1, closing the top of division B, and opening communication 20 between said division and the flue a, and actuating the lever H to throw the free edge of damper J against the partition d, whereby, the smoke and gases from the freshly burning fuel in division B, are conveyed 25 downward through the central flue a, and are passed up through the incandescent heat of the fire on the grate in division A, and thus in succession, the fuel is alternately supplied to the respective divisions of the fire-pot, and 30 the smoke and gases therefrom are consumed by being passed through the intense heat of the fire in the adjoining division. The sides of the fire-pot heat the flue to a high temperature, so that in passing therethrough the carbon is expanded and rendered more readily 35 combustible.

Having thus fully set forth my invention, what I claim as new, and desire to secure by Letters Patent, is—

40 1. In a furnace, in combination with the divisions of the fire-pot normally open at their top, of the reversible damper pivoted between said divisions and adapted to swing from one

division to the other and successively close the tops thereof. 45

2. In a furnace, the combination with the divisions of the fire-pot forming the central flue between them, of the reversible damper having the concaved head and adapted to alternately close the top of said divisions and 50 at the same time establish communication through said head between said central flue and the division closed.

3. In a furnace, the combination of the adjacent divisions of the fire-pot forming a flue 55 between them, the reversible damper adapted to alternately close the top of said divisions, and at the same time establish communication between the closed division and said flue, and close the communication between 60 said flue and the open division.

4. In a furnace, the combination of the adjacent divisions of the fire-pot forming the vertical flue between them, the lower end of which flue normally communicates with the 65 space below the grates of said divisions, the upper reversible damper adapted to alternately close the top of said divisions of the fire-pot, and at the same time establish communication with the respective divisions in 70 reciprocal succession, the lower damper adapted to successively open and close the communication between the central flue and the space below the grates of said divisions, and means connecting said dampers so that 75 they may operate simultaneously to pass the smoke and gases from one division through the fire in the other, and vice-versa, substantially as set forth.

In testimony whereof I affix my signature in 80 presence of two witnesses.

SHUBAEL T. ARMSTRONG.
